US00D989161S

(12) **United States Design Patent** (10) **Patent No.:** **US D989,161 S**
(45) **Date of Patent:** **** Jun. 13, 2023**

(54) **CAMERA HOUSING**

(71) Applicant: **Foresite Healthcare, LLC**, Maryland Heights, MO (US)

(72) Inventors: **Mark Schaumburg**, Columbia, MO (US); **George Chronis**, Chesterfield, MO (US); **Erik Stone**, Columbia, MO (US)

(73) Assignee: **Foresite Healthcare, LLC**, St. Louis, MO (US)

(**) Term: **15 Years**

(21) Appl. No.: **29/755,436**

(22) Filed: **Oct. 20, 2020**

(51) LOC (14) Cl. **16-05**

(52) U.S. Cl.

USPC **D16/237**; D16/221

CLAIM

The ornamental design for a camera housing, as shown and described.

DESCRIPTION

FIG. 1 provides a front right perspective view of a camera housing,

FIG. 2 provides a rear right perspective view thereof;

FIG. 3 provides a front view thereof;

FIG. 4 provides a rear view thereof;

FIG. 5 provides a right side view thereof;

FIG. 6 provides a left side view thereof;

FIG. 7 provides a top view thereof; and,

FIG. 8 provides a bottom view thereof.

The broken lines shown in the drawings depict portions of the camera housing that form no part of the claimed design.

1 Claim, 8 Drawing Sheets
